UNITED STATES PATENT OFFICE.

CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

SHOCKER FOR GRAIN OR THE LIKE.

1,234,803.

Specification of Letters Patent. Patented July 31, 1917.

Application filed April 15, 1914. Serial No. 831,931.

To all whom it may concern:

Be it known that I, CLEMMA R. RANEY, a citizen of the United States, residing at Chicago, in the county of Cook and State of Illinois, have invented certain new and useful Improvements in Shockers for Grain or the like, of which the following is a full, clear, and exact specification.

My invention relates to shockers for grain or the like.

It has for its object to provide improved means for building and setting a shock, which means are adapted to improve the construction and increase the efficiency of a shocking machine, and especially adapt it to use under service conditions. A further object of my invention is to set a shock in an improved manner whereby the butts of the sheaves forming the shock are set firmly upon the ground and a substantial shock is formed of such a character that it is not readily overturned. I attain these objects by the provision of an improved shocker having improved means for building the shock and improved means for setting the shock after it has been built and as the shocker moves forward, all of which will be more fully hereinafter set forth.

In order that my invention may be clearly and fully disclosed, I have illustrated in the accompanying drawings one embodiment which it may assume in practice. It is here, however, to be clearly understood that my invention is not necessarily limited in its embodiments to that shown herein for purposes of illustration.

In these drawings—

Figure 1 is a side elevation of a shocker equipped with my improvements; Fig. 2 is a plan view of such a shocker, a portion of the delivery mechanism being broken away;

Fig. 3 is a front elevation of the sheaf delivery mechanism shown connected to a binder;

Fig. 4 is a detail view of a portion of the sheaf delivery mechanism, showing the sheaf delivery member in a plurality of positions;

Fig. 5 is a detail view of one of the sheaf supporting springs;

Fig. 6 is a detail elevation of the dumping shock receptacle, showing the same in dumping position; and

Fig. 7 is a detail partial sectional view of one of the frame adjusting mechanisms.

The construction shown is of the general type described and claimed in my copending application Serial No. 573,106, filed July 21, 1910. It comprises a wheeled shocker frame 1, having a tongue 2 adapted to be 60 adjustably connected to a stubblewardly protruding support 3 projecting from beneath the binder deck 4 of a binder; the frame carrying the shocking mechanism being so operatively connected to the binder that it may 65 move independently thereof when passing over rough ground, and that the shocking mechanism thereon may receive power from the binder through a power shaft 5.

Carried upon an upstanding supplemental 70 frame 6, at the front of the frame 1, is a swinging sheaf delivery member 7 movable in a fore and aft direction through an upright plane. This member 7 acts to deliver in prostrate position in the shock receptacle, 75 hereinafter described, the sheaves ejected from the binder, these sheaves being turned butt end rearward as they are being delivered. It is shown herein in the form of a fork rotatable with a transverse shaft 8 in 80 bearings on the frame 6, and provided with a plurality of upstanding tines 9. This fork normally occupies the sheaf receiving position shown in Fig. 1, wherein it rests upon the support 3 in a plane beneath the plane 85 of the binder deck 4. Operatively connected to this fork through the shaft 8 are power connections, preferably of the type described in my copending application Serial No. 742,535, filed January 17, 1913, comprising 90 a split driving collar 10 enabling independent movement of the fork with respect thereto, a crank and resilient pitman connection 11, a power shaft 12, a chain and sprocket connection 13, a power shaft 14, and gearing 15 operatively connecting this last mentioned power shaft to the main power shaft 5. The movement of this fork is controlled by the sheaves delivered from the discharging 95 mechanism 16 of the binder.

The controlling mechanism therefor is of the type described in my copending application Serial No. 801,527, filed November 17, 1913, and includes a trip 17 normally extending upward through the binder deck 105 and pivoted beneath the latter. This trip is connected, through suitable link connections 18 and 19 and a crank connection 20, to a spring-pressed clutch controlling member 21, normally in operative position, and 110

controlling the connection of a clutch 22, which, in turn, controls the connection of the sprocket 13 to the power shaft 12, and thereby controls the connection of the fork 7 to the source of power. In a similar manner the fork is controlled by a supplemental controlling mechanism including a plurality of upstanding safety arms 23 spaced apart longitudinally from each other on a forwardly projecting rocking member 24 disposed on the stubbleward side of the fork and normally occupying the position shown in Fig. 3. This member 24 is, as shown, rotatably mounted at its front end on the support 3 and operatively connected at its rear end to the clutch controlling member 21 by means of a suitable flexible connection, such as a universal coupling 25, so that should a sheaf fail to actuate the clutch through the depression of the trip 17, that sheaf, upon engagement with the members 23 would still actuate the clutch to throw in the fork and raise the same from its sheaf receiving position. It is further obvious that the arms 23 will also act to stop the outward movement of the sheaf and thus cause the same to be always delivered upon the tined end of the fork.

In order to accurately position the sheaves with respect to the fork as the latter moves upward, and before its tines engage these sheaves, I have provided a plurality of cooperating sheaf positioning or supporting members or fingers 26-27 of the general type described in my copending application Serial No. 793,052, filed October 2, 1913, but especially adapted to use in connection with the arms 23. These members 26-27 are carried, respectively, upon the edge of the binder deck 4 and the upstanding safety members 23 on opposite sides of the plane of movement of the fork and above the sheaf receiving position of the latter. In the form shown the supports 26 are in the form of coiled springs spaced apart from each other longitudinally and projecting stubblewardly from the edge of the binder deck, their coiled portions being suitably attached to the binder deck at the points 28. The members 27 are likewise shown in the form of coiled springs, these springs having portions protruding grainwardly in substantially the same plane as the protruding portions of the springs 26, while their coiled portions encircle the members 23 and are attached thereto at 29. It is to be noted that these members 26-27 always underlie the sheaves, and are of such a length that the sheaves may not fall down between the same and be displaced with respect to the fork even should the sheaves strike the members 23 and force them back, means being provided which always insure a sheaf being properly positioned and supported with respect to the fork as the latter moves upward. Attention is also directed to

the fact that the supports do not in any way interfere with the fork in the operation of the latter, the springs not extending over the shank of the fork and being of such a character that should the tines of the fork strike them, these springs will be readily deflected out of the path of the tines. 70

In order to build a shock having a wide butt, the fork 7 is also provided with means for deflecting the same laterally as it moves to sheaf delivery position, of the type described and claimed in my copending application Serial No. 742,535, filed January 17, 1913. These means include an upstanding, swinging, U-shaped member or bail 30 rotatably mounted at its front end on the front of the frame 1 and having a short rear end or arm operatively connected, through a rod 31, adjustable links 32 and a link 33, with a plurality of pinions 34-35 journaled in suitable bearings on a supplemental support 36, which latter also serves as a support for the power shaft 12. As described in my copending application mentioned above, these pinions 34-35 are of different sizes and so connected that they impart to the bail 30 a swinging movement about its connection to the frame 1, the bail being thereby deflected laterally alternately in opposite directions. Through a suitable guiding connection between this bail and the fork 7, hereinafter described, as the latter is moved rearward in delivering successive sheaves, it is also successively deflected alternately to opposite sides of the cradle 100 in such a manner as to build a shock of the desired character mentioned. In my present improvement the long arm of this bail 30, instead of being rigidly mounted against lateral movement on the frame 1, is made 105 capable of yielding laterally by attaching it to the frame through a suitable cotter pin connection 37, whereby it may be rotated and also deflected about its point of connection to the frame toward the dotted line position shown in Fig. 3. As shown, it is also operatively connected to the front supplemental frame 6 at a point intermediate the ends of its long arm by a transversely disposed eye bolt connection 38 extending 115 through a longitudinally disposed bracket 39 projecting from the front of the frame 6, a coiled spring 40 surrounding the shank of the eye bolt and disposed between the bracket and the nut on the eye bolt, being 120 provided to hold the bail normally in the full line position shown in Fig. 3.

By this construction, even when straw is allowed to accumulate on the support 3 in such a manner as to interfere with the operation of the binder lock operating member 41, the accumulation of grain upon the support, and the consequent deflection of the fork, will not result in any bending of the bail or derangement of the mechanism. 130

For instance, if, when working under certain grain conditions, or for any other reason, the binder fails to properly bind a bundle, and through carelessness on the part of the operator, a sufficient amount of grain accumulates upon the support 3 to prevent the normal upward movement of the binder lock operating member 41 to lock the discharging mechanism of the binder after the fork 5 leaves it, obviously a sheaf may be discharged from the binder prior to the return of the fork, so that when the fork does come back it will strike this sheaf and rest thereon. If, under such circumstances, the bail 10 30 is so rigidly connected that it cannot yield laterally, when the next sheaf is discharged by the binder, it will force the fork 5 stubblewardly (Fig. 3) and the bail will then be bent laterally in such a manner that 15 20 in the next upward movement of the fork it will cause the latter to be so guided out of its normal path as to result in a general derangement of the mechanism. In the present construction, however, when under 25 such circumstances the sheaf strikes the fork, the bail will yield laterally with the fork and the latter, when raised, will be pulled back to its normal path by the spring 40, so that it will be guided back and forth 30 through its normal path under all conditions. Obviously, under such circumstances, since the fork will swing backward to sheaf delivering position without carrying a sheaf, the operator will also be thus notified that 35 it is necessary to clear the trash from the support 3.

I have also shown improved means for guiding the fork as it moves about its pivot, which are of a character facilitating the 40 movement of the parts and reducing the wear thereon. These means are shown to comprise brackets 42 fixed to one of the inclined shanks 43 of the fork in any suitable manner at a point adjacent the rear 45 end of the same and spaced apart from each other longitudinally thereon. These brackets carry between them longitudinally extending rollers 44, which are spaced apart and engagable with opposite sides of the bail 30. As shown, these rollers 44 are disposed at an angle of substantially 45° to the horizontal when the fork is in sheaf receiving position, and are so journaled in the brackets as to be freely rotatable upon engagement with the bail as the fork moves back and forth. Obviously, the brackets 42 may also, if desired, be made separately and separately attached to the fork, or may be made in one piece, as shown herein. 50 Further, it is obvious that the rollers 44 may be journaled upon these brackets in any suitable manner; as, for instance, by the nut and bolt connections 45 shown herein.

The controlling mechanism for the shock binding and discharging mechanism is con-

trolled by the size of the shock and actuated by the fork 7, being of the same type described and claimed in my copending application Serial No. 743,740, filed January 23, 1913. As shown, it comprises a ledge-like cam 46 eccentrically disposed with respect to the axis of the shaft 8 and mounted above the same, together with coöperating mechanism movable with the fork, and other mechanism actuated by said coöperating mechanism and connected to the controlling mechanism for the power connections. As shown and described in the above mentioned application, the fork shanks 43 are pivotally attached to a spacing block 47 fixed to the shaft 8 by a key 48. Further, a pivoted triangular tripping member 49 is pivoted upon the end of a radially extending crank or arm 50 fixed to the shaft 8 and movable with the fork. This member 49 has a roller 51 on one end which normally engages the upper surface of the cam 46 as the fork moves to sheaf delivering position, the member 49 being held in the desired position for such action by a spring 52 carried on the arm 50. When, however, the fork has passed down to sheaf delivering position, the member 49 is turned about its pivot 53 on the arm or crank 50 so that its roller 51 moves backward on the under surface of the cam when the fork is returned. Thus, as the fork moves back and forth while it builds up a shock, the roller 51 on the member 49, moving with the fork, alternately engages the upper and lower surfaces of the cam. When, however, the sheaves in the shock receptacle have reached a predetermined size, since the roller cannot then pass off the upper surface of the cam 46, it must be moved backward over the upper surface 105 of the cam by the fork driving mechanism, whereupon it engages a trip 54 pivoted on an arm projecting above the cam and preferably integral therewith, which trip is connected, through a link and spring connection 55, with a clutch controlling member 56 journaled on the machine frame and, in turn, operatively connected to a latch 57 controlling the connection of a clutch 58. This clutch 58, in turn, controls the connection of 110 the shock compressing, binding and discharging mechanism to the power shaft 14.

In my present improvement I have provided improved adjustable means for connecting the fork to the arm 50, whereby an improved rigid connection is established between the fork and the shaft 8 effectually preventing derangement of the mechanism by shifting of the fork with respect to that shaft, and which, by their adjustment, also enable the size of the shock to be adjusted as desired. These means are shown to comprise extensions 59—59^a on the spacing block 47 and the arm 50, respectively, at points substantially half way between the 115 120 125 130

fork shank pivots 60; the extension on one of the same, as, for instance, the block 47, being provided with an arcuate slot 61 through which it is adjustably connected by 5 a nut and bolt connection 62 with the arm 50 in such a manner that it may be rigidly attached thereto, and the relative angular position of the fork and arm may be adjusted as desired by loosening the nut and bolt connection 62 and adjusting the same 10 in the slot 61. It is here to be noted that by this connection means are provided whereby the fork is very accurately positioned upon the shaft 8, the improved connection between the arm and the fork acting as a supplementary connection coöperating with the key 48, which normally positions the fork 15 upon the shaft.

It is to be understood that the sheaf delivery member or fork 7 is operated in the usual manner described in my above mentioned applications, and that the spring mechanisms 64 and 65 therefor act in coöperation therewith in the manner described in my prior application Serial No. 742,535, filed January 17, 1913, cushioning the movement of the fork and accelerating the same at different stages in the movement of the latter. It is further to be understood that 20 the fork moves back and forth through arcs of gradually decreasing amplitude as it builds the shock under impact in the cradle, and that its tines are disengaged from the sheaves as they are deposited in the cradle by the quick return movement of the fork. 25 These features have been so fully discussed in my prior application mentioned above, and also a previous application Serial No. 573,106, filed July 21, 1910, that it here seems unnecessary to discuss them more fully. 30 Further, coöperating with the sheaf delivery member 7, and operatively connected thereto through suitable connecting mechanism above described as controlling the clutch 58, is mechanism for compressing, 35 binding and discharging the shock built by the fork of the general character therein described, which mechanism acts upon the sheaves when they are lying prostrate in the cradle or shock receptacle 66, while the latter occupies its normal or prostrate position 40 at the rear of the shocker frame. As in the construction described in the prior applications heretofore mentioned, the binding mechanism comprises a needle 67 mounted on the top of the stubbleward side of the frame and movable transversely across the latter to co-operate with a knotter 68. The compressing mechanism likewise comprises a compressor 45 arm 69 mounted on the top of the grainward side of the frame and operated by a cam 70 on the knotter shaft 71 to move transversely in such a manner as to co-operate with the needle and knotter. The cradle 50 or shock receptacle 66 is also operatively

connected to the rear end of the knotter shaft 71 through suitable crank and link connections 72—73, and a suitable latch connection 74 controlling the connection to these link connections of a transverse rock shaft 75 journaled on the rear of the frame 1 and having an arm underlying the cradle, which arm, upon the rocking of the shaft 75, tilts the cradle rearwardly to shock discharging position. All of these mechanisms are substantially as described in my applications mentioned above.

The shock receptacle is, however, mounted in an improved manner and operates in an improved manner through improved mechanism. As shown, instead of being pivoted upon the main or rigid frame 1, this receptacle is carried upon a supplemental, normally horizontally disposed, dropping or swinging frame 76 of substantially U-shape 80 which normally forms an extension of the frame 1 and is pivoted to the opposite sides of the rear end thereof at 77. This frame is normally supported in the position shown in Fig. 1 by an upwardly and forwardly extending latch member 78 resiliently connected at its upper end, through a spring and pin connection, 79, to one of the rear and grainward standards on the frame 1, and having on its rear end a latch 80 which is adapted to coöperate with a rearwardly and upwardly projecting latch member 81 fixed to the supplemental frame 76. As shown, this latch member 81 is movable between stops 81^a on the member 78, and is itself also 90 preferably provided with a slot 83, as shown, within the limits of which the latch member 78 is movable. The latch member 78 is also operatively connected, at a point intermediate its ends, to a part moving with the cradle 66, as by a link or other suitable connection 84, which is adjustably connected at 85 with a bracket 86 fixed on a suitable standard 87 on the cradle; such, for instance, as one of the standards for the 95 butt spreading tines described and claimed in my copending application Serial No. 743,562, filed January 22, 1913. Obviously, by adjusting this link connection 84—85, the point at which the frame 76 will be disengaged from the latch 78 may be adjusted as desired. Further, in order that the parts 100 may be returned to their initial positions, a spring 88 is provided, preferably operatively connected between a bracket 89, on the stubbleward side of the frame 76, and a fixed portion of the frame 1. In order to 105 return the frame 76 and assist in positioning the latch mechanism 74, the knotter shaft 71 and the movable parts of the clutch 58, a 110 spring 90 is also provided between the crank 72, on the rear end of the knotter shaft, and a bracket 91 on the grainward side of the frame 76.

It is, of course, to be understood that the 115

cradle or shock receptacle 66 is itself returned automatically to its normal position by a spring and chain connection 92 in the manner described in my above mentioned applications, the chain in this construction moving over a roller 93 journaled in a bracket 94 on the frame 1, so that it may move with greater facility and without any wear upon the frame. Further, it is to be understood that in a preferred form I use in this construction the normally upstanding, spring connected end tines 95 described therein, which end tines are pivoted at 96 at the rear of the cradle and controlled by a spring latch 97 automatically operable as the cradle is dumped, to release them from the cradle so that they may drop independently of the latter and underlie the shock as it is set upon the ground. Also I preferably use, in connection with this type of cradle, the head and butt piercing and positioning tines 98 and 99 (Fig. 1) described in my application Serial No. 801,526, filed November 17, 1913, the former being controlled by the automatic latch mechanism 100 described therein. However, it is to be understood that, if desired, these mechanisms may be omitted.

In order to cushion the shock receptacle 66 as it returns to its sheaf receiving position after the discharge of a shock, as in the manner described in my prior applications, I also provide a spring 101 operatively connected at its rear end to the frame member 76 and at its front end to an arm 102 fixed to the shaft 75, this spring normally acting to hold the arm on the shaft 75 in its upright position so that a roller 103 thereon is in contact with the bottom of the receptacle 66. In this construction, in order that the jar when the roller 103 contacts with the receptacle may be taken up to a still greater degree and the wear on the receptacle more evenly distributed, I also provide an inclined track 104 fixed to the receptacle bottom, as shown in Fig. 6. As in my prior constructions, the extreme or limit of backward movement of the cradle is established by stops 105 carried on the frame 1 (Fig. 1.)

The operation of the mechanism described is substantially the same as that described and claimed in my copending applications mentioned above. As the sheaves are delivered from the binder deck by the kicker forks 16 to their position above the fork 7 upon the spring supports 26-27, the fork is set in operation by its trip 17 or the safety trip members 23. As the fork moves backward it is deflected laterally about its pivot 60 through its connection with the bail 30, so as to deposit the sheaves in prostrate position, and with their butts to the rear, alternately upon opposite sides of the prostrate shock receptacle 66. As the shock is thus built up and the fork moves back and

forth, the roller 51 alternately engages with the top and bottom surfaces of the ledge-like cam 46 until a shock of the desired size is built up in the shock receptacle, this size being determined by the adjustment of the fork 7 and arm 50 relative to each other through the slot and bolt connection 61-62. Obviously, as hereinabove described, when the binder fails to bind the sheaves properly or the operator, through carelessness, permits straw to accumulate over the end of the support 3 and binder lock operating member 41, or even permits a bundle to lodge thereon, when the next bundle is discharged there will be no bending of the bail by the lateral movement of the fork, or other derangement of the mechanism, due to the improved connection 38, 39 and 40, the fork being deflected by the grain, and when raised returned to its normal position by the spring 40, so that it moves backward empty in such a manner as to notify the operator that it is necessary to clean the trash from the support 3. When a shock of the desired size has been built, the shock compressing, binding and discharging mechanisms operate in the manner described in the above mentioned applications, acting automatically to compress, bind and discharge the shock, the compressing and binding mechanism operating to compress and bind the sheaves in the cradle 66 into a shock, and the discharging mechanism then operating to tilt the cradle rearwardly to discharging position. However, as the cradle 66 is tilted rearwardly about its pivot, the supplemental frame 76 will be released through the action of the link 84, which, as the members 87 move backward, will be lifted and thereby raise the latch member 78 out of engagement with its coöperating member 81, so that the frame 76 will drop directly downward and the shock will be set positively upon the ground. In this movement the limits of movement of the member 81 will be, of course, established by the stops 81^a.

As hereinabove described, the point at which the frame 76 will drop may be determined by the adjustment of the adjustable connection 85. It may further be adjusted by the provision of any suitable adjusting mechanism for the frame 1; as, for instance, a rack and pinion connection 106 (Fig. 7) provided between the wheel supports 107 and the frame 1 and controlled by a suitable spring-pressed hand-operated locking member 108. Obviously, with such a construction the entire frame 1 may be raised or lowered with respect to the ground when working in long or short grain to adjust the mechanism within certain limits, and the breaking or dropping point of the supplemental frame 76 may be still further adjusted by adjusting the mechanism 85 so that, even under most extreme conditions, 130

the butts of the long grain will not be crumpled as the shock is set, and the short bundles will not be dropped through too long an interval before they strike the ground.

5 While I have described but one embodiment of my invention in this application, it is, of course, to be understood that the form shown is used for purposes of illustration and that the invention may be embodied in 10 other forms without departing from its spirit.

What I claim as my invention and desire to secure by Letters Patent is:

1. In a shocking machine, a frame, a 15 tilttable shock receptacle pivoted thereto and normally reclining thereon, means for tilting said receptacle to substantially vertical position, means for dropping said receptacle bodily downward as it approaches a vertical position, and means for varying at will the point at which said receptacle is dropped.

2. In a shocking machine, a frame, a supplemental frame pivoted thereto, a tilttable 25 shock receptacle pivoted on said supplemental frame, and latching mechanism normally locking said frames in a predetermined relation releasable upon tilting of said receptacle.

30 3. In a shocking machine, a frame, a supplemental frame pivoted thereto, a tilttable shock receptacle pivoted on said supplemental frame, and automatic latching mechanism normally positioning said frames in 35 predetermined relation releasable by said receptacle as it is tilted about its pivot.

4. In a shocking machine, a frame, a supplemental frame pivoted thereto, a tilttable shock receptacle pivoted on said supplemental frame, automatic latching mechanism 40 normally positioning said frames in predetermined relation releasable by said receptacle as it is tilted about its pivot, and means for returning the parts to their initial position.

45 5. In a shocking machine, a main frame, a supplemental frame operatively connected thereto, a shock receptacle pivoted on said supplemental frame and normally supported on said main frame, a locking mechanism intermediate said frames normally locking said frames in a predetermined relation, and operative connections between said supplemental frame and said receptacle operable 55 upon tilting of said receptacle for releasing said locking means.

6. In a shocking machine, a main frame, a supplemental frame pivoted at the rear thereof, a receptacle pivoted on said supplemental frame and normally reclining on said main frame, latching mechanism intermediate said frames normally holding the same in fixed relation, and controlling means for said latching mechanism movable with 60 said receptacle.

7. In a shocking machine, a main frame, a supplemental frame pivoted at the rear thereof, a movable shock receptacle pivoted on said supplemental frame and reclining on said main frame, latching mechanism 70 between said frames normally holding the same in a predetermined relation, and latch releasing mechanism operatively connected between said latching mechanism and said receptacle.

8. In a shocking machine, a frame, a supplemental frame pivoted thereto and extending rearwardly therefrom, a tilttable shock receptacle pivoted on said supplemental frame and normally reclining on 80 said first mentioned frame, means for locking said frames in predetermined relation, and means controlled by a movement of said shock receptacle for actuating said locking means.

9. In a shock receptacle, a frame, a supplemental frame pivoted thereto, a tilttable shock receptacle pivoted on said supplemental frame, means for imparting an angular movement to said shock receptacle about its 90 pivot, and means for imparting a vertical movement to said receptacle and pivot at any one of a plurality of positions in the movement of said receptacle about its pivot.

10. In a shocking machine, a frame, a supplemental frame pivoted thereon, a latch mechanism normally locking said frames in a predetermined relation, a shock receptacle pivoted on said supplemental frame, means for tilting said shock receptacle about its 100 pivot, means controlled by a movement of said shock receptacle for actuating said latch mechanism, and means for returning said supplemental frame and shock receptacle to their initial positions.

11. In a shocking machine, a frame, a supplemental frame pivoted thereon, a latch mechanism normally locking said frames in a predetermined relation, a shock receptacle pivoted on said supplemental frame, means for tilting said shock receptacle about its 110 pivot, means controlled by a movement of said shock receptacle for actuating said latch mechanism, and independent resilient means for returning said supplemental frame and shock receptacle to their initial positions.

12. In a shocking machine, a frame, a substantially U-shaped supplemental frame forming a continuation thereof and pivoted thereto, a latch member resiliently connected to said first mentioned frame, a co-operating latch member on said supplemental frame, a shock receptacle pivoted on said supplemental frame, and an adjustable link connection between said shock receptacle and said first mentioned latch member angularly movable with said receptacle to release said latch member as said receptacle is tilted.

13. In a shocking machine, a frame, a

horizontally disposed supplemental frame pivoted thereto, a normally reclining shock receptacle pivoted on said supplemental frame and extending over said first mentioned frame, a standard on said shock receptacle, a latch member resiliently connected to said first mentioned frame extending rearwardly and downwardly therefrom, a coöperating latch member on said supplemental frame, and a link connection operatively connected between said latch member and said standard on said shock receptacle.

14. In a shocking machine, a frame, a horizontally disposed supplemental frame pivoted thereto, a shock receptacle pivoted on said supplemental frame and normally reclining on said first mentioned frame, a standard on said shock receptacle, a latch member resiliently connected to said first mentioned frame extending rearwardly and downwardly therefrom, a coöperating latch member on said supplemental frame, an operative connection between said first mentioned latch member and said standard on said receptacle, and means for adjusting the length of said connection as desired.

15. In a shocking machine, a frame, a horizontally disposed supplemental frame pivoted at the opposite sides thereof, a tilting receptacle pivoted on said supplemental frame and normally extending over said first mentioned frame, a latch member operatively connected to said first mentioned frame and extending rearwardly over said supplemental frame, a coöperating latch member on said supplemental frame, and latch controlling means operatively connected to said first mentioned latch member and said receptacle and movable with said receptacle as the latter is tilted.

16. In a shocking machine, a frame, a shock receptacle pivoted thereon, means for moving said receptacle about its pivot including a swinging arm normally tending to engage with the bottom of said receptacle, means for automatically returning said receptacle to its initial position, and means including an inclined track carried on the bottom of said receptacle engageable by said arm for cushioning said receptacle in its return to initial position.

17. In a shocking machine, a frame, a shock receptacle pivoted thereto and normally reclining thereon, means including a swinging arm having a roller thereon underlying said receptacle for tilting the same about its pivot toward shock discharging position, and an inclined track carried on the bottom of said receptacle and engageable by said roller as said receptacle is returned to normal position.

18. In a shocking machine, a frame, a shock receptacle pivoted thereto and normally reclining thereon, means including a

vertically movable resiliently connected arm underlying said receptacle for tilting the same about its pivot, a roller on said arm, resilient means for returning said receptacle to its normal reclining position, and an inclined track carried on the bottom of said receptacle engageable with said roller as the receptacle is returned to normal position at the highest point in the working surface of said inclined track.

19. In a shocking machine, a frame, a normally reclining movable shock receptacle pivoted thereon, a sheaf delivery member pivoted on said frame and movable in an upright plane in building a prostrate shock in said receptacle, automatic means for operating said delivery member and operating said shock receptacle when a shock built therein has reached a predetermined size, and means for adjusting the size of said shock as desired.

20. In a shocking machine, a frame, a normally prostrate shock receptacle pivoted thereon, a swinging sheaf delivery member carried by said frame and movable through a substantially upright plane in delivering sheaves to said receptacle, operating mechanism for said sheaf delivery member, means including controlling mechanism carried by said sheaf delivery member for tilting said receptacle when the sheaves therein have reached a predetermined height, and means for adjusting at will the time of tilting of said receptacle comprising means for adjusting angularly the relation of said delivery member with respect to said controlling mechanism.

21. In a shocking machine, a frame, a shaft journaled thereon, a swinging fork movable with said shaft and extending radially therefrom, a member fixed to said shaft and movable therewith, and adjustable connections between said fork and said member whereby the angle between said fork and member may be adjusted at will.

22. In a shocking machine, a frame, a shaft journaled thereon, a radially protruding member fixed to said shaft and rotatable therewith, a sheaf delivery member protruding radially from said shaft, and means for attaching said sheaf delivery member to said first mentioned radially extending member whereby the angle between said members may be varied as desired.

23. In a shocking machine, a frame, a shaft journaled thereon, a laterally protruding member fixed to said shaft and rotatable therewith, a sheaf delivery member protruding radially from said shaft, means for attaching said sheaf delivery member to said first mentioned radially extending member whereby the angle between said members may be varied as desired, and supplemental means for attaching said sheaf delivery member directly to said shaft.

24. In a shocking machine, an upwardly movable normally prostrate sheaf delivering member, operating mechanism therefor, a normally upright sheaf barrier disposed at 5 one side of the plane of movement of said sheaf delivery member, and a plurality of sheaf supporting fingers carried on said barrier at points above said delivery member projecting laterally from said barrier toward the plane of movement of said delivery member.
25. In a shocking machine, an upwardly movable normally prostrate sheaf delivering member, operating mechanism therefor, 15 a normally upright sheaf barrier disposed at one side of the plane of movement of said sheaf delivery member, and a plurality of resiliently mounted sheaf supporting fingers carried on said barrier at points above said delivery member projecting laterally from said barrier toward the plane of movement of said delivery member.
26. In a shocking machine, an upwardly movable normally prostrate sheaf delivering member, operating mechanism therefor, a 25 normally upright sheaf barrier disposed at one side of the plane of movement of said sheaf delivery member, and a plurality of longitudinally spaced resilient sheaf supporting fingers carried on said barrier at points above said delivery member projecting laterally from said barrier toward the plane of movement of said delivery member.
27. In a shocking machine, an upwardly 35 swinging, normally prostrate sheaf delivering member, operating mechanism therefor, controlling mechanism for said operating mechanism including a plurality of upstanding arms longitudinally spaced apart and disposed at one side of said sheaf delivering member when the latter is in prostrate position, and a plurality of resiliently mounted sheaf supporting members projecting laterally from said arms and toward the plane 40 of movement of said sheaf delivering member.
28. In combination, a binder, a binder deck thereon, a shocking machine operatively connected to said binder, a swinging sheaf delivery member carried on said shocking machine normally disposed in prostrate 45 position in a plane beneath the edge of said binder deck, operating mechanism for said sheaf delivery member, controlling mechanism therefor including an upstanding sheaf barrier projecting upward on the opposite side of the plane of movement of said sheaf delivery member from said binder deck, and a plurality of series of sheaf supporting 50 members carried on said binder deck and on said upstanding sheaf barrier projecting laterally in opposite directions toward the plane of movement of said sheaf delivery member.
29. In combination, a binder, a binder 55 deck thereon, a shocker operatively connected to said binder, an upwardly movable sheaf delivery member normally positioned in a plane beneath said binder deck, a plurality of upstanding supports disposed on 60 the opposite side of said sheaf delivery member from said binder deck when said sheaf delivery member is in normal position, and a plurality of series of resiliently mounted oppositely extending sheaf supporting members carried on said supports and on the edge of said binder deck in a plane above said sheaf delivery member and protruding toward the plane of movement of the latter.
30. In a shocking machine, a frame, a 75 swinging sheaf delivery member pivoted thereon and movable about its pivot, a guiding bail therefor mounted on said frame, operative connections between said delivery member and bail, and means intermediate 80 said bail and frame whereby said bail may be deflected bodily laterally upon deflection of said delivery member.
31. In a shocking machine, a frame, a 85 sheaf delivery member pivoted thereon and movable in a substantially upright plane, an upstanding guiding bail therefor mounted on said frame, operative connections between said delivery member and bail, and means intermediate 90 said bail and frame whereby said bail may be deflected bodily laterally about its pivot upon deflection of said delivery member.
32. In a shocking machine, a frame, a 95 swinging sheaf delivery member pivoted thereon and movable about its pivot, a guiding bail therefor mounted on said frame, operative connections between said delivery member and bail, means intermediate 100 said bail and frame whereby said bail may be deflected bodily laterally upon deflection of said delivery member, and means for returning said bail to its initial position as said delivery member is moved about its pivot.
33. In a shocking machine, a frame, a 105 swinging sheaf delivery member pivoted thereon and movable about its pivot, a guiding member operatively connected thereto and pivoted on said frame, mechanism for deflecting said guiding member laterally 110 about its axis to deflect said sheaf delivery member, and spring mechanism intermediate 115 said guiding member and frame whereby the former may yield bodily laterally upon premature deflection of said sheaf delivery member.
34. In a shocking machine, a frame, a 120 swinging sheaf delivery member pivoted thereon and movable about its pivot, a guiding member operatively connected thereto and pivoted on said frame, mechanism for deflecting said guiding member laterally 125 about its axis to deflect said sheaf delivery member, and spring mechanism between said guiding member and frame whereby 130

after a premature lateral deflection bodily of said sheaf delivery member and guiding member the same are returned to their normal positions as the sheaf delivery member is moved about its pivot.

35. In a shocking machine, a frame, a swinging sheaf delivery member pivoted thereon and normally prostrate thereon, mechanism for oscillating said member about its pivot, mechanism for deflecting said member laterally as it moves about its pivot including an upstanding swinging bail pivoted on the frame, and resilient connections between said bail and frame whereby upon a lateral deflection of said sheaf delivery member when in prostrate position said bail may yield bodily laterally and be returned with said sheaf delivery member to normal position upon the elevation of said sheaf delivery member.

36. In combination, a binder, sheaf discharging mechanism thereon, binder locking mechanism controlling said discharging mechanism including an operating member, a shocker operatively connected to said binder, a sheaf delivery member pivoted thereon and normally actuating the operating member of said binder locking mechanism at intervals, mechanism for oscillating said sheaf delivery member about its pivot, and means for maintaining said sheaf delivery member in its normal path of operation in delivering a sheaf despite the premature operation of said binder locking mechanism by the accumulation of grain on the operating member and the lateral displacement of said delivery member by a sheaf discharged from the binder.

37. In combination, a binder, a laterally

extending support thereon, a shocking machine operatively connected to said binder, a pivoted sheaf delivery member on said shocking machine normally lying upon said support, means for oscillating said sheaf delivery member about its pivot, sheaf discharging mechanism on said binder, binder locking mechanism controlling the same including an operating member carried on said support and normally operable by said sheaf delivery member, deflecting mechanism for said sheaf delivery member as it moves about its pivot, and means operatively connected thereto for returning said sheaf delivery member to its normal path of operation as it delivers a sheaf after a lateral deflection of said delivery member by a sheaf prematurely discharged from said binder due to the premature operation of said binder lock operating member by grain accumulating on said support.

38. In a shocking machine, a frame, a swinging sheaf delivery member pivoted thereon, mechanism including a laterally swinging bail carried on said frame for deflecting said sheaf delivery member laterally as it moves about its pivot, and a plurality of guiding rollers fixed to said sheaf delivery member and engageable with the opposite sides of said bail transmitting the deflection of said bail to said sheaf delivery member.

In testimony whereof I affix my signature, in the presence of two witnesses.

CLEMMA R. RANEY.
